SHEET-FEEDING MACHINE.

1,154,406.

Specification of Letters Patent. Patented Sept. 21, 1915.

Continuation in part of application Serial No. 790,169, filed September 17, 1913. This application filed January 24, 1914. Serial No. 814,096.

To all whom it may concern:

Be it known that I, HOWARD K. KING, a citizen of the United States, residing at Philadelphia, in the county of Philadelphia, 5 State of Pennsylvania, have invented a new and useful Sheet-Feeding Machine, of which the following is a specification.

This invention relates to improvements in sheet feeding machines.

10 The object is to provide improved means for separating and delivering single sheets from a pile of sheets.

The improvement relates to that type of feeding machine commonly known as the 15 continuous feed type.

Referring to the drawings which illustrate merely by way of example, suitable means for embodying my invention—Figure 1 is a plan view. Fig. 2 is a side elevation. Fig. 3 is a section on line 3—3 of Fig. 20 showing the cone friction and the operating diaphragm on slightly enlarged scale. Fig. 4 is a rear elevation. Fig. 5 is a front elevation. Fig. 6 is a section on line 6—6 25 of Fig. 2, showing pivot and latch members of the valve trip mechanism on an enlarged scale. Fig. 7 is a side elevation of most of the part shown in Fig. 6. Fig. 8 is a section on line 8—8 of Fig. 19 on an enlarged scale 30 showing the rod and bar that operate the valve trip to form a clamp on the sheets when the feeder is not operating. Fig. 9 is a section on line 9—9 of Fig. 1, showing the entire machine in section. Fig. 10 is a section 35 substantially on line 10—10 of Fig. 2. Fig. 11 is a section on line 11—11 of Fig. 5 on an enlarged scale and showing the front part of the feeder only. Fig. 12 is a similar view of some of the parts shown in Fig.

40 11, but in a different position. Fig. 13 is a plan view of one of the members for latching up the valve, on a still larger scale. Fig. 14 is a section on an enlarged scale of one of the air passages from the rail to the valve 45 casing. Fig. 15 is a section on line 15—15 of Fig. 10 on an enlarged scale. Fig. 16 is a section showing some of the parts shown in Fig. 12, but in a different position. Fig. 17 is a section showing some of the members 50 shown in Fig. 15, with the latch member in a different position. Fig. 18 is a section on line 18—18 of Fig. 17. Fig. 19 is a vertical section near the center of the machine, showing the sheet detector and associated mecha-

nism. Fig. 20 is a rear view of the upper 55 end of the detector arm. Fig. 21 is a similar view of some of the parts shown in Fig. 19, with the members in a different position. Fig. 22 is a view showing some of the parts shown in Fig. 19, with some of the members 60 in a different position. Fig. 23 is a plan view on an enlarged scale of the combing wheel and device for clamping the sheets, and the drag weight, the combing wheel and mounting being shown in section. Fig. 65 24 is a section on line 24—24 of Fig. 23. Fig. 25 is a section on line 25—25 of Fig. 23. Fig. 26 is a section on an enlarged scale on line 26—26 of Fig. 4. Fig. 27 is a section on line 27—27 of Fig. 26; also showing connecting mechanism not shown in Fig. 26. Fig. 70 28 is an enlarged front elevation of the middle portion of the machine. Fig. 29 is an enlarged sectional detail of the pad provided in the table beneath the combing 75 wheel (sheet 8).

Similar numerals refer to similar parts throughout the several views.

Referring to Figs. 2 and 9, 30 is the receiving table upon which a pile of sheets 31 80 having been first feathered is placed in the manner well known in the art. These sheets are placed upon the table 30 and fed downwardly toward roller 32 by the tapes 33 passing over the surface of table 30 around 85 drum 32 over idler 34 and pulleys 35. The sheets are carried around the drum 32 between said drum and the tapes 36 which pass around roller 37, pulleys 38, roller 39 and pulleys 40. The sheets passing between 90 tapes 33 around drum 32 and tapes 36 are delivered upon the feeding table 41 over which pass the carrying tapes 42. Carrying tapes 42 pass around roller 39 and pulleys 43. By means of the carrying tapes 42 the 95 sheets are carried forward beneath the combing wheel 44 by which they are fed forwardly toward the drop and feed rollers 245 and 246 respectively of the folding machine or similar device.

100 The present invention comprises improved means in connection with such feeding devices as herein illustrated for controlling the operation of the combing wheel and the drag weight, and means for interrupting the 105 movement of the sheet, and the latching means for the drop roller of a folding machine or similar device to bring the same

into proper operative relationship with the feeder.

The invention also comprises improved means for the automatic control of the delivery of sheets to the feeding roller 246, means for adjusting the several instrumentalities to suit sheets of different characteristics and improved means for guiding the sheets from the first table to the second table 10 as for example, around the drum 32.

The combing wheel is of usual construction and is mounted on the stud 45 which projects from the framework 46 which is mounted in the casing 47 and has a rocking 15 movement about shaft 48, see Fig. 23. Secured to the combing wheel 44 is the gear wheel 49 which co-operates with the gear wheel 50 which is mounted on shaft 48 and rotates therewith. The outer end of stud 45 20 is supported by the connecting arm 51 which is connected at its upper end with the lever 52, said lever 52 being rotatably fixed with shaft 53. Shaft 53 also carries arm 54 having adjustable contact piece 55, see Fig. 11, 25 which is controlled by the movement of piston rod 56 carrying piston 57 controlled by diaphragm 58 in the pneumatic head 59. Rigidly secured to the shaft 53 is the arm 222, see Fig. 2; to the outer extremities of 30 which is secured the serrated bar 223, with which the adjustable bracket 224 engages. To bracket 224 is secured the spring 225; the other end of which is secured at a fixed point 226. By moving the bracket 224 along 35 the serrated bar 223 from one side to the other of shaft 53 or toward or away from shaft, the pressure exerted by the combing wheel upon the sheets may be modified as desired.

40 A pad is secured across the table 41 extending transverse the direction of travel of the sheets and just beneath the combing wheel 44, see Figs. 15 and 29. This pad is sunk in a channel in the table 41 and the 45 top surface of the pad is substantially flush with the top surface of the table. In construction this pad preferably comprises a resilient cushion 219^a such as felt. Beneath the front edge of this cushion or pad 219^a, 50 that is, the edge toward which the sheets travel, is secured a smooth fabric 220^a, such as mole skin. This fabric is folded upwardly and over the pad 219^a and is fastened to the table 41 slightly to the rear of 55 the pad 219^a as at 221^a, see Fig. 29. The mole skin affords a good wearing surface which does not interfere with the travel of the sheets over table 41, and the pad eliminates the noise ordinarily due to the impact 60 of the combing wheel upon the sheets when resting or supported immediately beneath the combing wheel, by non-yielding material. The jar thus eliminated, greatly adds to the wear of the working parts and the 65 smooth operation of the machine. This pad

structure is important where the pile beneath the combing wheel is thin, where however the pile operated upon by the combing wheel is thick such cushioning device is of less importance.

The feeding of the feathered bank to the combing wheels.—The cam 76 is mounted on the shaft 77, see Fig. 11, which cam is constantly driven during the operation of the machine. The lever 73 is pivotally mounted 75 at 74 and is provided at its free end with the roller 75 adapted to engage with the periphery of the cam 76. The roller 75 of lever 73 is normally maintained against the periphery of the cam 76 by means of the 80 spring rod 78 provided with the spring 79. To lever 73 is connected one end of the connecting rod 80, the other end being connected with the stud 83 on friction element 81, see Figs. 2 and 3, so that by the normal 85 operation of the rod 80 actuated by the cam 76 the friction element 81 will be made to rock backward and forward. The positive actuation of the cam gives the feeding motion. The return motion of the rod is due 90 to the spring 79. The friction element 81 is journaled free on the shaft 82 and is connected by a collar with the lever 84 pivotally supported at one end on the adjustable stud 85 and pivotally connected at its free end at 95 86 to the piston rod 87 of piston 88 in pneumatic head 107. Lever 84 is also connected with the spring 108. The external clutch member 109 is keyed to the shaft 82. When compressed air is admitted to the head 107 100 the piston and piston rod are pushed forward causing the engagement of the clutch elements 81 and 109 and the consequent actuation of shaft 82. When air is exhausted from the head 107 the piston moves to the left in response to the tension of spring 108 causing the disengagement of the clutch elements 81 and 109, or in the absence of the spring the pressure between the friction elements is sufficiently relieved to prevent their 105 effective co-operation. A sheet detector controls the supply of compressed air to the diaphragm head 107 as hereinafter described. Through means of a lever the descent of the drop and feed rollers raises the detector finger thus opening wide the exhaust from the diaphragm. This causes the clutch to be released, and as stated above, the friction clutch element 81 is returned by the spring 110 actuated cam arm. The positive actuation by the cam gives the forward feeding motion. The return motion of the cam arm is 115 spring controlled. Should the clutch be engaged the spring 79 does not have sufficient power to move the feeding drum. This is important, otherwise under certain conditions the bank would receive a reverse feed and be moved back and forth with the oscillations of the friction.

The shaft 82 is provided with the gear 89 130

which meshes with gear 90 on shaft 91 which carries the drum or roller 32 see Fig. 9. Gear 90 meshes with gear 92 on shaft 93 which carries pulleys 38. It will thus be seen that the actuation of shaft 82 secures the actuation of the drum 32, pulleys 38 and 39, and carrying tapes 33, 36 and 42, and thus secures the desired feed of sheets from table 30 to the desired position beneath the 10 combing wheel 44 on table 41.

Means for the manual or arbitrary actuation of shaft 82 is provided in the crank handle 94 shown in Fig. 4.

It will be noted that with reference to Fig. 9, that each pulley 40 is mounted on a sliding member 95 which has a sliding movement in ways provided in the stationary framework. Each member 95 is connected with one end of a tension spring 96. The other end of spring 96 is attached to the rod 97 secured to the stationary framework. This structure permits of an independent tension of each of the tapes 36 and permits tapes 36 to move away from or toward the drum 32 to accommodate the thickness of the pile of sheets passing around drum 32 and between said drum 32 and tapes 36.

It will be noted that roller 37 is placed well above drum 32. The advantage of this arrangement is that roller 37 permits a free passage of the sheets from table 30 and tapes 33 beneath the said roller 37, whereas if this roller rested against the drum 32 it would 35 tend to obstruct and buckle the sheets passing around the drum.

The advantage of having the adjustable tapes 36 travel around the drum 32, instead of stationary guides which has hitherto been common, is that the tapes not only yield readily to accommodate variations in the thickness of the pile passing around drum 32, but they also tend to keep the sheets well smoothed out and assist the travel thereof, 45 while stationary guides about drum 32, present a dead surface to one side of the pile; thus a substantially even and uniform feed is given to both sides of the pile by the tapes 33 and drum 32 on the one side and of the 50 tapes 36 on the other side. The tapes 36 guide the pile of sheets and deliver same onto tapes 42 and table 41.

Automatic control of the means for feeding the feathered bank to the combing wheel.—It will be understood that the continuous rotation of cam 76 causing the continuous reciprocation of rod 80 and actuation of friction member 81 would normally cause a continuous step by step rotative movement of shaft 82 if the friction elements 81 and 109 were always in frictional engagement during the positive actuation of friction 81 by the cam 76. As above stated, however, the engagement of the friction elements is controlled by a sheet detector con-

trolling a pneumatic operation of the friction member 81. This detector finger 63 is shown in Figs. 19 and 21, and forms the upper member of a caliper device. The lower member of this caliper is a plate or bar 64 of considerable length. The rear end of this plate is secured to the feed board 41. The forward end, which is under the contact part of the finger 63, is free to be adjusted vertically. This adjustment is secured by the set-screw 65 bearing against the underside of the plate. The knurled head of this screw is under the feed board, the screw projecting upwardly through a threaded plate 66. This plate being secured to the feed board. The pneumatic head which controls the movable friction element 81 is controlled by air pressure from reservoir 213 passing through the minute opening 68 into chamber 69 which communicates with the conductor 70 leading to the pneumatic head 107. Chamber 69 is also provided with the aperture 71 which is adapted to be obstructed by the upper end 72 of the arm 110 pivoted at 111 normally controlled by the spring 112 which is adjustably connected with the serrated bar 113. To arm 110 is connected arm 67 carrying the detector finger 63. Normally gravity with the aid of the spring 112 holds the detector finger either in contact with the paper, or causes the upwardly extending arm 110 to bear against the exhaust nozzle. When the exhaust nozzle is thus closed or partially closed, the pressure of air through the aperture 68 is communicated to the diaphragm of the head 107 causing the engagement of the friction elements 81 and 109 and the consequent feeding of the bank of sheets. When the number of sheets however passing between the caliper elements 63 and 64 are sufficient to raise the caliper elements 63 slightly the end 72 is withdrawn from the nozzle 71 and thus opening the exhaust from the diaphragm causes the clutch 110 to be released. It is also to be noted that the cam 76 is timed to feed during the portion of the cycle allotted to the combing action and permit the return of the friction element while the sheet is being taken away by the drop and feed rollers. This is accomplished by means of the lever 114 pivoted at 115 having an adjustable weighted end 129 adapted to engage the arm 163 moving with the drop roller 245. Lever 114 has an extension 130 which is adapted to engage the arm 110 and force the end 72 away from the nozzle 71, thus opening wide the exhaust from the diaphragm of head 107 and causing the clutch to be released, and as stated above, the spring returns the cam actuated arm.

It will be understood that very minute variations in the thickness of the pile of sheets beneath the detector finger 63 will

effect the engagement between the friction clutch elements, that is to say, the efficiency of such engagement will depend largely upon the efficiency of the closure of the opening 71. This closure may only be partial or not absolute, and there will result therefrom a slipping frictional engagement between said frictional elements. This results in an extremely responsive and delicate control of the feeding of the bank of sheets onto the table 42, which is distinctly different from the rigid feed resulting from positive gear such as pinions or such mechanism as a pawl and ratchet. As is well known, motion transmission means, comprising co-operating friction elements, between which there is a slipping frictional engagement, is capable of transmitting motion very gently, especially at the start, and where the pressure of engagement is comparatively slight. The less the pressure of engagement between the friction elements, the greater the slip, and consequently the gentler is the communication of motion. With a pneumatic control for this frictional engagement an extremely delicate and sensitive control is secured. In the actual operation of the machine the aperture 71 is not entirely closed, hence there is more or less slip between the friction elements, and from this it follows that the feed of sheets is always a gentle one without danger of forcing the sheets from the rear under the forward sheets.

The manual adjustment of the screw 65 determines the thickness of the bank maintained at the caliper point. The detector finger 63 has a longitudinal adjustment on the arm 67 permitting the caliper point to be moved toward or away from the drop roller 245. The extremes of this adjustment are arbitrarily fixed. The object of this adjustment is to handle advantageously papers of varying thicknesses and of different characteristics.

When handling thin paper the combing action penetrates to and sets in motion quite a number of sheets, in some cases a dozen or more. For thin and all ordinary easy combing paper, the caliper point should be well back, away from the drop roller. For fairly thick, firm paper it should be set in an intermediate position. For soft, hard combing paper, stock where the combing action penetrates for only two or three sheets deep, the caliper point should be set to the closest position to the drop roller.

In order to get a successful automatic feeding action, the caliper point must not be farther from the drop roller than will form steps of a reasonable length between the sheets in motion. Thus, three sheets in motion means three steps, provided the caliper device will not permit more than three sheets to pass under it without stop-

ping the feeding action of the bank. When so set, the starting of one or more additional sheets under the caliper will cause the swinging of the arm slightly away from the escape nozzle. This exhausts the air from the diaphragm sufficiently, and thus prevents the clutch engaging and feeding the bank forward. The cam operating the feed through the clutch has an arbitrary motion. The feeding of the bank is arrested by the action of the detector caliper when the bank is brought sufficiently forward, the cam swinging the clutch member idly for the balance of the stroke. This results in the bank being fed forward the required amount. In this connection it should be noted that by this pneumatically controlled actuation of the friction it is possible for the friction to release at any point or any moment of its rotative movement, that is to say, there is no fixed or required degree or arc through which the friction actuation of the drum is caused by the positive movement of the cam. The moment the end 72 is sufficiently actuated to relieve the opening 71 the frictions will begin to slip or entirely separate as the case may be whether in the beginning or at the end of the stroke or in any intermediate position.

Usually, after the withdrawal of each sheet the bank will be fed forward a greater or less amount, changing in response to the varying steps in the feathered bank. This variation is due to the manner in which the sheets are placed on the receiving board by the operator. A number of sheets may reach the detector without being feathered at all. In this case the feeding of the bank is entirely arrested until the sheets are worked out and delivered by the successive actions of the combing wheels.

As mentioned before, for thin or easy combing paper the detector fingers should be well back from the drop roller. In this case there should be from eight to twelve steps between the caliper and the drop roller, the number depending somewhat upon the character of the paper. Normally these steps are very short just as the edge passes beyond the caliper, and gradually lengthen out as it approaches the drop roller.

Bearing in mind that the sheet whose edge is just passing the caliper is the eighth to the twelfth from the top, while the one next to the drop roller is the top sheet; when the caliper finger is adjusted the proper distance from the drop roller to suit the character of paper, as described, the combing wheels will have little or no influence on the sheets whose edges have not yet reached the caliper point.

The reason for, and the importance of, the longitudinal adjustment has been shown. Experiment has proved that there is considerable latitude in the position of the de-

tector, with reference to the drop roller, for any particular paper, the greatest latitude being with ordinary easy combing paper, and the least latitude with very soft, hard 5 combing paper.

With a little experience the operator should be able to set the detector in a good working position by examining the paper to be worked. The caliper should be set rather 10 closer than the combined thickness of the number of sheets representing the expected number of steps. Then, with the machine in operation, the caliper should be slowly opened up and adjusted until good working 15 conditions are secured.

Body 47 is provided with a lug 99 provided with the recess 100 as shown in Figs. 23 and 24. This recess is adapted to receive the end of rod 101 which is secured therein 20 by the pin 102 which permits a pivotal movement about the pin 102 in recess 100. The rod is also provided with the aperture 103 to receive the end of latch pin 104 when the rod 101 is carried to the elevated position. 25

Fig. 24 shows the rod 101 in the lower or operative position which is normally maintained by gravity. Upon the rod 101 is slidably mounted the member 105 which is 30 adapted to be clamped to said rod in the required position by the clamp screw 106. A feather and key-way are provided between the body 105 and the bar 101 to prevent relative turning between the two. 35

Clamping the back of the top sheet, said sheet being in position to be withdrawn by the action of the feed and drop rollers.—This clamping is accomplished by action of the drag wheel 127. Suitably mounted on 40 the structure connected to the body or member 105 is the pneumatic head 116 provided with a nozzle 117 and the diaphragm 118. This diaphragm is adapted to engage and operate the piston 119 and piston rod 120 45 connected therewith. At the lower end of the piston rod 120 is secured at one end a lever 122, which is pivotally mounted at 123. Lever 122 is provided with an extension 124 having a braking surface 125 and 50 a detent 126 adapted to co-operate with the periphery of the wheel 127. This wheel 127 is mounted on the free end of arm 128 which is pivotally connected at 129 with a bracket 121 which is connected with the 55 pneumatic head 116. The wheel 127 is provided with a toothed or serrated periphery and is adapted normally to rest by gravity upon the pile of sheets. When pressure is exerted above the diaphragm 118 the piston rod 120 is depressed and the brake arm 124 engages the periphery of wheel 127 to 60 stop its rotation. The pressure of the wheel upon the paper is also thereby increased, thus forming an effective brake or clamp 65 upon the pile of sheets. When the wheel

127 is free to rotate it serves as a slight drag only to the advancing sheets. When the top sheet has passed beyond the influence of this wheel, it is in position to be removed by the drop and feed roller and the combing 70 wheel is through operating on the same. Before the drop and feed roller begins to act on said top sheet the brake is applied to wheel 127 which serves to clamp the balance of the pile of sheets as above described, 75 and prevents their displacement as the top sheet is being removed therefrom, and while the combing wheel is elevated. In the present example, two of such clamping wheels are used, one back of each combing wheel. 80

When it is desired to move the entire structure, comprising the wheel 127 and the drag foot 131, the outer end of rod 101 is elevated about the pivot support 102 until the aperture 103 comes into register with 85 the pin latch 104, the engagement therewith maintaining the said elevated position until again operated.

When in the lower or operative position the rod 101 and the devices supported thereby are supported by the roller 196 secured to the outer end of extension 235 connected to bracket 107. This roller 196 is adapted 90 normally to rest upon the pile of sheets.

Adjustment.—It will be understood that 95 the wheel 127 should be so positioned, when in the operative position, as to engage the pile of sheets immediately to the rear of the first sheet when said sheet is in position to be operated upon by the drop and feed 100 roller. This position is secured, in accordance with the size of the sheets operated upon, by the adjustment of the body 105 on the rod 101, which adjustment is maintained by the set-screw 106. 105

The air pressure is delivered to the diaphragm chamber 116, through nozzle 117, to which is connected the flexible tubing 132 from a source of air pressure supply, 110 controlled by a valve hereinafter to be described.

Control of head 116.—The control of air pressure to and exhaust from head 116 is secured by means of the piston valve 195 and piston 236, see Fig. 19. The valve piston 236 115 is connected by a link 200 with a stud 201 connected to lever arm 114. The lever 114 is controlled by the movement of the arm 163 connected with the drop roller 245. When the drop roller descends the valve piston 236 120 is carried to its lower position, by the movement of lever arm 114 establishing communication between the air pressure supply in 213 and the pneumatic head 116, thus causing the braking and clamping of wheel 127 at 125 the moment of the descent of the drop roller 245. Upon the elevation of the feed roller the valve piston 236 is elevated and communication is cut off between 213 and 116 120 and open between 116 and the exhaust, thus 130

releasing the brake on wheel 127 and relieving the pressure of the wheel.

Valve control of the diaphragm heads controlling the combing wheel.—It will be understood that when the top sheet has been combed forward into the final combing position, when the feed and drop rollers are ready to act upon the same, the combing wheel is elevated from said sheet, and as above described, the brake is made to engage the clamp wheel 127 on the pile to the rear of said sheet, so that the drop and feed rollers may remove said top sheet from the pile. It has already been explained that the movement of the combing wheel and the operation of the brake are secured by the actuation of pistons in pneumatic or diaphragm heads by the introduction of air pressure to said heads. The control of said air pressure to the combing wheel heads is secured by a valve controlled mechanism actuated by the sheet itself, when it assumes said final position between the drop and feed rollers. Such a mechanism is illustrated in the drawings especially Figs. 11 and 12. Secured to the stationary framework, is a valve casing 133. This valve casing is provided with ports, and a valve piston 134, and is adapted by the operation of the piston member to establish communication between the source of air pressure supply 135 and the conductor 136 (Fig. 5) to the two diaphragm chambers 59 already described, so that when pressure is thus communicated to the upper sides of the diaphragm the pistons are depressed as already described. The valve piston 134 is adapted to be actuated to interrupt communication between the source of air pressure supply and the diaphragm chambers, and also to open communication between said diaphragm chambers and the exhaust, in order to relieve the pressure in said diaphragm chambers and permit the diaphragm and piston rods to assume normal positions. When the pressure is relieved from the chamber 59 above the diaphragm 58 the weight of the combing wheel structure operating through arms 52 and 54 on piston rod 56 returns piston 57 and diaphragm 58 to the elevated position as shown in Fig. 11.

In Fig. 14 the chamber 135 is shown connected with the reservoir 213 by the channel 217 located in the side frame of the machine.

The means for actuating the valve piston will now be described. The member 137 is pivotally supported at 138, see Figs. 11, 12 and 13, and is adapted in one position to engage the lower end of the valve piston 134 to maintain the same in the elevated position as shown in Fig. 11. It is also adapted to assume a position withdrawn from the valve piston 134 to permit said piston, due to gravity and the action of spring 227, to as-

sume the depressed position as shown in Fig. 65 12. The actuation and control of this member 137 is secured as follows: The lever 139 is mounted on rock shaft 140, and its free end 141 is adapted to engage the member 137. To the same rock shaft 140 is secured the 70 arm 142 having its free end provided with a roller 143, and also connected with the spring push rod 144. The roller 143 is adapted to engage the cam 145 which is adapted to rotate constantly. The periphery of the cam 75 is provided with a short depression 146 so that with each revolution of the cam 145 the roller 143 drops into said depression and causes an elevation of the levers 139 and consequently the elevation of the members 137 80 for a short interval during each cycle of the machine.

It will be understood that in the elevated position of the valve piston 134, communication between the supply of air pressure 85 and the diaphragm heads 59 is interrupted, and communication between the diaphragm heads and the exhaust is established.

The shaft 147 is shown as hollow and rectangular in form and is mounted at its outer ends on the pivot pins 148, see Figs. 6, 7, 15, 16, 11 and 12. This shaft 147 is in two parts, see Fig. 5, being similarly supported at the middle of the machine. In other respects the two parts are the same. At the outer end of each element of shaft 147 is provided a finger or arm 149, and also the arm 150 which is connected with the spring 151 for maintaining the shaft in its normal pivotal position. The spring 151 100 is secured to an adjustable rod 152. Each section of shaft 147 is provided with a structure comprising a yoke 153 which is adapted to be clamped in any position of adjustment along the shaft 147 by means 105 of the clamp-screw 154. To this clamping yoke are secured the guide 155 and the wing 156 to which the finger 157 is adjustably secured by means of the slot and bolt 158. These yokes are secured in the proper position of adjustment on the shaft elements 147 so that the fingers 157 will register with any desired grooves 159 of the feed roller 246, said roller being provided with a number of 110 said grooves to suit the various sizes of sheets operated upon. Until the advancing sheet comes between the drop roller 245 and the feed roller 246, the finger 157 will project into the groove 159 as shown in Fig. 11, and the arm 149 will engage the member 137 and hold the same in the elevated position irrespective of the movements of the lever 139. When, however the sheet, which is indicated at 160 in Fig. 12, passes over the feed roller 246, the finger 157 is lifted thereby and the shaft 147 is consequently rotated, carrying the arm 149 into the position shown in said Fig. 12, so that it will 115 120 125

register with aperture 161 and the member 137 will fall into the position shown in Fig. 12, the member 149 projecting through aperture 161. In this position the valve 5 piston 134 falls by force of gravity or the actuation of spring 227, and establishes communication between the source of air pressure and the diaphragm heads, causing the depression of piston rod 56 and the consequent elevation of the combing wheel.

After the sheet is withdrawn beyond the finger 157, the finger is ready to fall back into the channel 159 of feed roller 246 upon the release of arm 149 upon the next elevation 15 of member 137 by the operation of lever 139 and cam 145, whereupon the said member 137 is held into the latched position by said arm 149 until again released by the passage of the next sheet between the feed 20 roller and finger 157.

On practically all paper, except paper that is extremely hard to comb, it is desirable to have more or less weight on the bank. This weight should rest on the bank several 25 steps or sheets back of the top sheet. They serve a double purpose; one to retard the rear or under sheets, and thus increase the separation or steps in the upper sheets; the other purpose is to give a constant resistance 30 to comb against, thereby making the "hard" and "soft" spots in the bank less marked. It is a well known fact that a pile or bank does not comb uniformly; frequently combs quite easily in some places, 35 and quite hard in other places; changing suddenly from one condition to the other. The drag, acting with a constant resistance, decreases the percentage of variation between the extreme conditions of hard and 40 soft places.

The pressure on the combing wheels is set to comb against the natural resistance of the paper, plus the resistance caused by the pressure of the drag. With hard combing 45 paper, where only a very few sheets are acted upon at a time, it is desirable to use little or no drag weight. On paper where the combing influence extends deeper into the bank, it is desirable to use considerable 50 weight, as a resistance or drag to prevent or lessen the motion of the sheets deeper down.

The explanation given above shows the advantages gained by using the drag. However, the machine can be adjusted to operate 55 without it. In practice, the changing of the pressure due to weight or spring on the drag is one of the adjustments most frequently made in operating the King pile feeder. It is one of the adjustments used to secure the 60 proper length of steps in the combed-out sheets.

The pressure weight now under consideration is provided with a diaphragm, see Figs. 23, 24 and 25. This diaphragm is rigidly

attached to the part bearing on the bank. It also forms part of the weight. All the weight bearing on the paper is direct gravity. There are two of these pressure devices complete, one back of each combing wheel. Each one is provided to carry extra 70 weights for example, 202 and 203. However, it is expected that with one of these weights on each device, practically all kinds of paper can be successfully handled.

The adjustment consists in the control of 75 the amount of air admitted to the diaphragm head. These diaphragm heads are so arranged that they are lifted when sufficient compressed air is admitted to them, the inclosed piston and piston rod remaining stationary.

The diaphragm or pneumatic head is rigidly secured to the sleeve 204 which carries the presser foot 205. The pin 206 is rigidly secured to the outer casing 207 which is adjustably connected with the bracket 107. When air pressure is admitted to the head 197 above the diaphragm piston 208 piston rod 209 being in engagement with pin 206 it follows that the said piston rod can have 85 no further downward movement, the result is, that the diaphragm head 197, tube 204 and presser foot 205 are correspondingly lifted. The hollow tube 204 is provided with slots as at 210 to permit relative movement between said tube to the fixed pin 206. The result is that as the pressure is increased above the diaphragm 208 the pressure of the 90 presser foot is relieved. In this way it follows that the pressure exerted by presser foot 205 is gradually relieved as the pressure in the diaphragm head increases. By this arrangement only one set of valves is necessary to control both heads. This set 95 consists of two valves, a needle valve and a balanced piston valve. The piston valve is operated by the vertical movement of the left hand combing wheel.

Rear pressure weights or drag weights.—
This valve and valve operating mechanism 110 is illustrated in Fig. 11. The valve piston 62 is provided with a suitable casing having chambers connected one with the source of air supply 213 and the other connected with the diaphragm head 197. The piston 62 is 115 adapted to establish communication between the air pressure supply and the diaphragm head in one position and between the cut off of said communication and establish communication between the diaphragm head 120 and exhaust in the other position. The piston is actuated by the contact piece 61 secured on the arm 60 which is mounted on the shaft 53. When the combing wheel is down, the valve connects the compressed air supply with the diaphragm heads. When 125 the combing wheel is up, the valve shuts off the supply of air to the diaphragm heads,

and instantly exhausts the air pressure in them to the atmosphere. The compressed air, before reaching the piston valve, passes through a needle valve 199. The manual adjustment of this needle valve constitutes the adjustment of the drag weight; this adjustment alone being sufficient for working from the easiest to the hardest combing papers.

- 10 For easy combing paper the needle valve should be open only slightly. Under this condition, when the combing wheels go down, the drag weight is very slowly lifted, just as slowly as the operator may desire.
- 15 The greater part of the weight of the drag being on the paper when the combing wheels first come into action, this weight more or less rapidly becomes lighter during the combing interval.
- 20 For hard combing paper the needle valve may be opened quite wide, with the result that the drag is lifted clear of the paper about the time the combing wheels reach the paper. When the valve is so adjusted,
- 25 the drag weight would not have any influence in retarding the combing action of the wheels.

With the needle valve the operator can quickly get any speed in lifting, from a movement barely noticeable to the quickest speed required. The adjustment of the needle valve is made with the machine in operation, so that the result of any change in adjustment can be quickly seen. The adjustment of the needle valve is equivalent to changing the weight of the drag; but the operation of lifting the drag, and thus changing the weight of the drag during the combing interval does more than that. Its effect is to automatically take care of the hard and easy combing parts of the bank, without the operator making frequent adjustments to suit the varying conditions. The explanation of how this is accomplished is as follows:—The combing wheels are arranged to remain in action upon the sheet until the sheet is brought into position under the valve trip fingers at the feed roller. If this time exceeds the part of the cycle allowed to combing action, it will cause a miss in feeding, the sheet being taken away on the succeeding cycle of the machine. When the machine is properly adjusted, the normal time of combing will not exceed half of the time allowance. The hard combing parts of the bank will require more than normal time; the easy parts less than normal. The weight of the drag is gradually lessened during the combing. For illustration, consider that it is lifted clear of the paper at the end of the normal or average combing time. In this case the additional combing time, when working on a hard combing place, will be under the most favorable condition, having no drag resistance to

comb against. On the other hand, when an easy combing place is encountered, the wheels remain down less than the normal time, perhaps half of the normal time. In this case the entire combing will be against the resistance of the drag. This increases the length of steps over what they would otherwise be. It also increases the interval of time that the wheels remain down over what it would otherwise be. In other words, it shortens the long combing interval, and lengthens the short combing interval. It shortens the length of the steps that go with a hard combing place; and lengthens the steps that go with an easy combing place.

It may be explained here that easy combing places tend to make short steps, more sheets being in motion; and hard combing places tend to make long steps, a less number of sheets being in motion. A heavy drag resistance means less sheets in motion, while a light drag resistance means more sheets in motion. It will thus be seen that a gradually lifting drag weight effects a valuable automatic balance to the combing action.

The control of the feeding of the bank by the pneumatic caliper controls the number of sheets stepped out so nicely that it somewhat lessens the importance of the drag just described. However, the two work in entire harmony.

The drop roller 245 is normally actuated to reciprocate in the usual way by means of the cam 162 as shown in Fig. 2. To prevent however the drop roller from assuming the operative position, before the sheet has become squarely presented between the drop and feed rollers, latching means are provided, also controlled by the fingers 157. For this purpose the drop roller supporting structure is provided with the arm 163, having a latching edge or contact piece 164. The two latching fingers 165 and 166, see Figs. 19, 21, 22 and 28 are mounted on studs pivoted to the stationary framework. These latching members are normally held against the face of arms 168 by counterweight 167. The purpose of this arrangement is as follows:—As above described, the drop rollers are reciprocated by the cam 162 and raised and lowered with each cycle of the operation of the machine. If, when the fingers 157 are raised by the paper entering between the drop and feed rollers, the drop rollers are in the extreme elevated position, the latching members 165 and 166 are free to respond to the movement of the shaft 147. If however, the shaft elements 147 are rocked by the fingers 157 after the drop rollers are freed by cam 162 to fall, that is, with the latch contact 164 resting upon the said latches 165 and 166, the latches will not be withdrawn from said latch contacts 164. In other words the drop rollers can only be released to operate upon the sheet after the 130

sheet has squarely assumed its final position between the drop and feed rollers while the said drop rollers are in the extreme elevated position; or in other words, if the fingers 157 have been actuated by the sheet after the cam 162 has permitted the contact members 164 to rest on the latches 165 and 166 to prevent their disengagement, the sheet after assuming its final position must wait 10 until the cam 162 has again lifted the drop rollers so that the latches 165 and 166 are released. It will also be noted that there are two fingers 157, one controlling one element of shaft 147, the other controlling the other 15 element of shaft 147, and that latch 165 is controlled by one section of shaft 147, while latch 166 is controlled by the other section. This results in requiring the entire front of the sheet to be squarely presented to final 20 position before both latches can be actuated to release the drop rollers.

Rod 169 is pivotally connected with the free end of arm 170, which is rigidly secured to shaft 171, see Figs. 1, 10 and 15. Arms 172 and 173 are in the present instance an integral structure, and are rigidly secured to shaft 171. Arms 174 and 175 are also an integral structure and are loosely mounted on shaft 171. Arm 172 is provided with the lug 176 adapted to encounter arm 175. To arm 173 is secured one end of spring 177. The other end of spring 177 is secured to the lower end of arm 174. The pin 178 projects from arm 54. When shaft 171 is turned in the clockwise direction by operating rod 169 arm 173 is moved to put spring 177 under tension, so that when arm 54 is depressed the lug or stud 178 is engaged by latch arm 175 and the combing wheel is locked in the elevated position until shaft 171 is again turned. Arm 179 is rigidly mounted on shaft 171, located about the middle of the machine, and is secured to the connecting rod 180 which in turn is secured to arm 181, see Figs. 15 and 19. Arm 181 is rigidly mounted on the stud 182 which is rotatably mounted in the stationary bracket 183, see Figs. 15 and 28. Arm 184 is also rigidly secured to stud 182. Arm 184 is provided with a lug 186 which is adapted to encounter arm 185. Spring 187 is secured between the lower end of arm 184 and the arm 185. To the outer end of arm 185 is pivotally connected one end of connecting rod 188, see Figs. 8 and 15. Connecting rod 188 is guided in a projection of bracket 183, see Fig. 8, and is connected at its lower end with a pivoted cross-bar 189, adapted to encounter the arms 168. The operation is that the bar 189 pressing upon the arms 168, Fig. 22, turns shaft 147 to depress the clamping guide 155 against the sheet; the purpose being to prevent the creeping of the sheets toward the drop and feed rollers, when the machine is not feeding sheets.

At the same time latch pieces 235^a and 236^a are brought into engagement, see Fig. 16. Arm 190 is integral with arm 181. Arm 191 is loosely mounted on stud 182, and arm 192 is integral with arm 191. Arm 191 is connected by spring 193 to the outer end of arm 190. Arm 190 is provided with a lug 194 adapted to engage arm 191, see Fig. 22. Thus when the rod 169 is operated to depress the clamping guide 155, the arm 192 is brought into engagement with latch 166 to maintain the same in the latching position and to maintain the drop roller 245 in the elevated position as shown in Fig. 22. 70 75

As indicating the importance of controlling the feed of the bank of sheets by the condition of the sheets stepped out close to the drop and feed rollers, that is, by a detector located at this point the following is given as an illustration. Where the operator places a pile of sheets on the top table 30, not having been sufficiently feathered out, that, with a plurality of the sheets in approximate register, when these sheets come down to the detector 63 they are there arrested. No further feed can take place until the combing wheel has combed or stepped these sheets out so that they can be taken singly by the drop and feed rollers. 80 85 90

Blowing nozzles 215 are provided as shown in Fig. 10, and are supplied by the hose 216 from the pipe 217. These nozzles are adapted to deliver wind to the sides of the bank of sheets at proper intervals during the operation of the machine, but it is important that the blasts of wind be cut off when the operation of the machine is stopped, that is, when the combing wheels are locked in the elevated position. For this purpose the following mechanism is provided: Referring to Figs. 26 and 27, a valve 218 and valve piston 219 are provided to control the air delivered to said nozzles. The piston 219 is controlled by the spring 220 and normally held in the elevated position establishing communication between the source of air pressure supply and the nozzles. Above the piston 219 is the rod 221 having a loose connection with the pin 222^a on the end of lever 227^a pivoted at 228. On the shaft 171 is provided the collar 229 which is adapted to engage the end 230 of lever 227^a. When the shaft 171 is turned to lock the combing wheels in the elevated or inoperative position, the collar 229 engages the end 230 and depresses the same causing the elevation of the pin 222^a which causes the corresponding elevation of the rod 221. Upon the elevation of the rod 221 the spring 220 serves to elevate the piston 219, which serves to cut off communication between air pressure supply and the nozzles. When the shaft 171 is returned to normal position, permitting the depression of rod 221, the weight of the rod overcomes the tension of

spring 220 and carries the piston 219 into the lower position, establishing communication between the air pressure supply and the nozzles.

5. By the use of the term drum in the claims, I mean to include a roller or other equivalent rotating feeding device.

What I claim is:—

1. Means for feeding a bank of sheets comprising a feed drum, a friction element operatively connected therewith, a coöperating friction element and means for rocking the same, means for controlling the coöperation of said friction elements comprising a sheet actuated detector.

2. A sheet feeding device comprising a drum, actuating means therefor comprising friction elements, means for causing a varying efficiency of engagement between the said coöperating friction elements controlled by a sheet actuated caliper device.

3. A sheet device for feeding a bank of sheets comprising a drum, actuating means therefor comprising friction elements, means

25 for controlling the efficiency of engagement between the said coöperating friction elements comprising a sheet actuated caliper device, means for adjusting the caliper device with respect to the thickness of 30 the bank of sheets permitted to pass beneath the same.

4. A sheet feeding device for feeding a bank of sheets comprising a drum, actuating means therefor comprising friction elements, means for controlling the efficiency of engagement between the said coöperating friction elements comprising a sheet actuated caliper device and means for adjusting the position of the caliper device with respect to its distance from the front edge of the forwardmost sheet.

5. Means for feeding a bank of sheets comprising a drum, actuating means therefor comprising coöperating friction elements, pneumatically operated means for controlling the coöperation of said elements and a sheet detector for controlling the air pressure on the pneumatically operated device.

50 6. Means for feeding a bank of sheets comprising a rotating drum, actuating means therefor comprising coöperating friction elements and a pneumatic device for controlling the coöperation of the friction elements, and a sheet actuated trip for controlling the pneumatic device.

60 7. Means for feeding a bank of sheets comprising a rotating drum, actuating means therefor comprising coöperating friction elements, a pneumatic device for controlling the coöperation of the friction elements, an air exhaust and control therefor connected with a pneumatic device, and a sheet actuated trip for operating the control.

65 8. Means for feeding a bank of sheets

comprising a rotating drum, actuating means therefor for comprising coöperating friction elements, a pneumatic device for controlling the coöperation of the friction elements, an exhaust connected with the 70 pneumatic device and a sheet caliper device for controlling the exhaust.

9. Means for feeding a bank of sheets comprising a rotating drum, actuating means therefor comprising coöperating friction elements, a pneumatic device for controlling the coöperation of the friction elements, an exhaust connected with the pneumatic device and an adjustable sheet caliper device for controlling the exhaust.

75 10. A sheet feeding machine comprising a rotating drum, actuating means therefor comprising coöperating friction elements, means for actuating one friction element, a sheet detector for controlling the coöperation of the friction elements, means for adjusting the detector with respect to the combined thickness of the several sheets permitted beneath said detector.

80 11. A sheet feeding machine comprising a 90 rotating drum, actuating means therefor comprising coöperating friction elements, means for actuating one friction element, a sheet detector for controlling the coöperation of the friction elements, means for adjusting the detector with respect to its distance from the front edge of the forwardmost sheet.

100 12. A sheet feeding machine, drop and feed rollers for coöperating therewith, a sheet caliper device in proximity with the drop and feed rollers, means for advancing the bank of sheet toward the caliper device, means for actuating the sheet advancing means comprising coöperating friction elements, pneumatic means for controlling the coöperation of said friction elements and means, controlled by the caliper device, for controlling the pneumatic means.

110 13. The combination of a rotatable drum, actuating means therefor comprising coöperating friction elements, means for effecting the coöperation of said friction elements, comprising a pneumatically operated piston, 115 a source of air pressure connected therewith, an exhaust or air escape between the source of air pressure and the piston, a control for said escape and a sheet detector connected with said control.

120 14. The combination of a rotatable drum, actuating means therefor comprising coöperating friction elements, means for effecting the coöperation of said friction elements, comprising a pneumatically operated piston, 125 a source of air pressure connected therewith, an exhaust or air escape between the source of air pressure and the piston, a control for said escape and a sheet caliper, one element of which is connected with said control.

15. The combination of a rotatable drum, actuating means therefor comprising coöperating friction elements, means for effecting the coöperation of said friction elements, comprising a pneumatically operated piston, a source of air pressure connected therewith, an exhaust or air escape between the source of air pressure and the piston, a control for said escape and a sheet caliper, one element of which is operatively connected with said control, and means for adjusting the caliper with respect to the thickness of the bank permitted to pass between its elements. 70
16. The combination with drop and feed rollers of a rotatable drum, actuating means therefor comprising coöperating friction elements, means for effecting the coöperation of said friction elements, comprising a pneumatically operated piston, a source of air pressure connected therewith, an exhaust or air escape between the source of air pressure and the piston, a control for said escape and a sheet caliper, one element of which is connected with said control, and means for adjusting the caliper elements with respect to their distance from the drop and feed rollers. 80
17. The combination with a drop and feed roller of a rotatable drum, actuating means therefor comprising coöperating friction elements, means for effecting the coöperation of said friction elements, comprising a pneumatically operated piston, a source of air pressure connected therewith, an exhaust or air escape between the source of air pressure and the piston, a control for said escape and a sheet caliper, one element of which is connected with said control, means for adjusting the caliper elements with respect to their distance from the drop and feed rollers, and means connected with the drop and feed rollers for controlling said exhaust. 90
18. Means for advancing a bank of sheets comprising a rotating roller or drum, actuating means therefor comprising coöperating friction elements, pneumatic means for varying the pressure of coöperation of said friction elements, an air escape connected with said pneumatic means and a sheet actuated detector for controlling the air escape. 100
19. Means for advancing a bank of sheets comprising a rotating roller or drum, actuating means therefor comprising coöperating friction elements, pneumatic means for varying the pressure of coöperation of said friction elements, an air escape connected with said pneumatic means and a sheet actuated detector and a member having operative relationship therewith for modifying said air escape. 110
20. Means for advancing a bank of sheets comprising a rotatable drum, actuating means therefor comprising friction elements, one of which is positively geared with the drum, means for rocking the other friction element in one direction positively, in the other direction by a spring when the said friction elements are not in operative contact and pneumatically controlled means for controlling the coöperation of the friction elements. 120
21. Means for rotating a bank of sheets comprising a rotatable drum, actuating means therefor comprising friction elements, pneumatic means for controlling the coöperation of the friction elements, and a sheet detector for controlling the pneumatic means whereby the friction elements may release at any point of the rotative movement of the drum. 130
22. Means for rotating a bank of sheets comprising a rotatable drum, actuating means therefor comprising friction elements, pneumatic means for controlling the coöperation of the friction elements, and a sheet detector for controlling the pneumatic means whereby the friction elements may release at any moment of the rotative movement of the drum. 140
23. The combination of a rotatable drum, actuating means therefor comprising coöperating rotative elements, means for effecting the coöperation of said rotative elements, comprising a pneumatically operated piston, a source of air pressure connected therewith, an exhaust or air escape between the source of air pressure and the piston, a control for said escape and a sheet detector connected with said control. 150
24. In a sheet feeding machine, the combination of two sheet receiving tables, one arranged above the other, a drum between the two tables and pneumatically controlled drum actuating means for carrying the sheets from one table to the other. 160
25. In a sheet feeding machine, the combination of two sheet receiving tables, one arranged above the other, a drum between the two tables and tapes coöperating with the drum for carrying the sheets around the drum from one table to the other, means for actuating the drum including a friction clutch and pneumatically operated means for controlling the clutch. 170
26. In a sheet feeding machine, the combination of a combing wheel, means for lowering and raising the same, a table for supporting the sheets and a pad set into the table beneath the combing wheel having its top surface substantially flush with the top surface of the table, said pad comprising a substance of yielding material such as felt, and a covering of smooth surface material such as mole skin so as to permit the free movement of the sheets over the pad and at the same time eliminate the shock of the combing wheel as it descends upon the pile of sheets. 180

27. In a sheet feeding machine, the combination of a table for supporting the sheets to be fed, a combing wheel for operating upon the pile of sheets, pneumatically controlled means for feeding the sheets to the combing wheel and a sheet detector near the front of the pile for controlling the pneumatic means.

28. In a sheet feeding machine, the combination of a table for supporting the sheets to be fed, a combing wheel for operating upon the pile of sheets, means for feeding sheets to the combing wheel comprising a friction device and a sheet detector near the front of the pile of sheets for controlling the friction device.

29. In a sheet feeding machine, the combination of two sheet receiving tables, one positioned above the other, a drum operating between the two tables and coöperating tapes for carrying the sheets from the upper table to the lower table, means for supporting said tapes yieldingly to accommodate variations in thicknesses in the pile of sheets passing around the drum, means for positively actuating said tapes also to travel at a speed substantially corresponding to the peripheral speed of the drum to maintain the sheets well smoothed out and to assist the travel thereof.

30. In a sheet feeding machine, the combination of two sheet receiving tables, one positioned above the other, a drum operating between the two tables and coöperating tapes for carrying the sheets from the upper table to the lower table, means for supporting said tapes yieldingly to accommodate variations in thicknesses in the pile of sheets passing around the drum, and means for actuating the tape supporting means to cause the movement of the tapes at a speed corresponding substantially to the peripheral speed of the drum to secure a substantially even and uniform travel and feed to both sides of the pile of sheets.

31. In a sheet feeding machine, the combination of a sheet supporting table, sheet actuating means, a freely rotatable pressure wheel engaging the pile of sheets to the rear of the sheet actuating means, and means for locking said wheel against rotation and adding to the pressure thereof.

32. In a sheet feeding machine, the combination of a sheet supporting table, sheet actuating means, a freely rotatable pressure wheel engaging the pile of sheets to the rear of the sheet actuating means, and means for locking said wheel against rotation controlled by the advancing sheet.

33. In a sheet feeding machine, the combination of a sheet supporting table, a combing wheel, means for raising and lowering the combing wheel, a freely rotatable drag wheel resting upon the pile of sheets to the rear of the combing wheel, a braking device

for locking the drag wheel against rotation, and pneumatically operated mechanism controlled by the advancing sheet for controlling the combing wheel elevating means, and the braking device.

34. In a sheet feeding machine, the combination of a sheet supporting table, sheet actuating means, a drag wheel adapted to rest upon the pile of sheets, a pivotally supporting frame for said drag wheel to permit the wheel to accommodate unevennesses in said pile, a braking device connected with said frame for locking the wheel against rotation, and means controlled by the advancing sheet for actuating the braking device.

35. In a sheet feeding machine, the combination of a sheet supporting table, sheet actuating means, a drag wheel adapted to rest upon the pile of sheets, a pivotally mounted supporting frame for said drag wheel to permit the wheel to accommodate unevennesses in said pile, a braking device connected with said frame for locking the wheel against rotation, and means controlled by the advancing sheet for actuating the braking device, said supporting frame adapted to move to carry the wheel into the inoperative position, and latching means for maintaining said inoperative position.

36. In a sheet feeding machine, the combination of a sheet supporting table, a combing wheel, means for raising and lowering the combing wheel, a drag wheel adapted to rest by gravity upon the pile of sheets to the rear of the combing wheel, and adapted normally to rotate freely as the sheets pass beneath the same, and means for locking the wheel against rotation when the top sheet of the pile is free therefrom.

37. In a sheet feeding machine, the combination of a sheet supporting table, a combing wheel, means for raising and lowering the combing wheel, a drag wheel adapted to rest by gravity upon the pile of sheets to the rear of the combing wheel, and adapted normally to rotate freely as the sheets pass beneath the same, and means for locking the wheel against rotation when the combing wheel has been raised from the pile of sheets.

38. In a sheet feeding machine, the combination of a sheet supporting table, means for moving the sheets thereon, drop and feed rollers for removing the advancing sheet therefrom, a drag wheel resting by gravity on the pile of sheets and normally adapted to rotate freely as the sheets pass beneath the same, and a braking device for locking the wheel against rotation before the drop and feed rollers operate upon the advancing or top sheet.

39. In a sheet feeding machine, the combination of a sheet supporting table, means for moving the sheets thereon, drop and feed rollers for removing the advancing sheet therefrom, a drag wheel resting by gravity on the pile of sheets and normally adapted to rotate freely as the sheets pass beneath the same, and a braking device for locking the wheel against rotation before the drop and feed rollers operate upon the advancing or top sheet.

feed rollers for removing the advancing sheet therefrom, a drag wheel resting by gravity on the pile of sheets and normally adapted to rotate freely as the sheets pass beneath the same, a braking device for locking the wheel against rotation before the drop and feed rollers operate upon the advancing or top sheet, and means for adjusting the position of the drag wheel to the size of the sheets operated on, so that the same will be effective on the pile immediately to the rear of the first or forward-most sheet when said sheet is in position to be operated upon by the drop and feed rollers.

40. In a sheet feeding machine, the combination of a sheet supporting table, a combing wheel, a drag wheel adapted to rest on the pile of sheets, pneumatically operated means to raise the combing wheel from the pile of sheets and pneumatically operated means to brake the drag wheel against rotation at the same time the combing wheel is raised.

41. In a sheet feeding machine, the combination of a sheet supporting table, a combing wheel, a drag wheel adapted to rest on the pile of sheets, pneumatically operated means to raise the combing wheel from the pile of sheets and pneumatically operated means to brake the drag wheel against rotation at the same time the combing wheel is raised, and actuating fingers controlled by the advancing sheets for controlling the pneumatically operated means.

42. In a sheet feeding machine, the combination of a sheet supporting table, a combing wheel, a drag wheel adapted to rest on the pile of sheets, pneumatically operated means to raise the combing wheel from the pile of sheets and pneumatically operated means to brake the drag wheel against rotation at the same time the combing wheel is raised, a piston valve controlling the passage of compressed air to the pneumatically actuated means, and an actuating finger controlled by the advancing sheet for controlling the valve piston.

43. In a sheet feeding machine, the combination of a sheet supporting table, sheet actuating means, a freely rotatable pressure wheel engaging the pile of sheets to the rear of the sheet actuating means and pneumatically operated means for braking the wheel and adding to the pressure exerted thereby on the sheets.

44. In a sheet feeding machine, the combination of a sheet supporting table, sheet actuating means, a freely rotatable pressure wheel engaging the pile of sheets to the rear of the sheet actuating means, and sheet controlled pneumatically operated means for braking the wheel and adding to the pressure exerted thereby on the sheets.

45. In a sheet feeding machine, the combi-

nation of a sheet supporting table, sheet actuating means, a freely rotatable pressure wheel engaging the pile of sheets to the rear of the sheet actuating means, a pneumatic head and piston for braking the wheel and adding to the pressure thereof, and a roller for normally supporting said pneumatic head.

46. In a sheet feeding machine, the combination of a sheet supporting table, a combing wheel, drop and feed rollers and a clamping guide, actuating levers, and means for establishing operative relationship therebetween whereby the combing wheel and drop roller may be rendered ineffective and the clamping guide effective to prevent creeping of the sheets when it is desired to interrupt the feeding.

47. In a sheet feeding machine, the combination of a sheet supporting table and a combing wheel, pneumatically operated means for causing the elevation of the combing wheel and arbitrary means for rendering effective a latch for locking the combing wheel in said elevated position.

48. In a sheet feeding machine, the combination of a sheet supporting table, a combing wheel, drop and feed rollers and a clamping guide, means for arbitrarily locking the combing wheel and drop roller in the elevated or inoperative position and the clamping guide into the clamping position and for arbitrarily releasing said elements.

49. In a sheet feeding machine, the combination of a sheet supporting table, a combing wheel, drop and feed rollers and a clamping guide, manually operated means for locking the combing wheel and drop roller in the elevated or inoperative position and the clamping guide into the clamping position and for arbitrarily releasing said elements.

50. In a sheet feeding machine, the combination of a sheet supporting table, a combing wheel, means for locking the combing wheel in elevated position, blowing nozzles for delivering currents of air between the front edges of the sheets, a valve for controlling the air supply thereto and means having operative relationship with said locking means, whereby the air supply is interrupted when the combing wheel is inoperative.

51. In a sheet feeding machine, the combination of a sheet supporting table, a combing wheel, means for raising and lowering the combing wheel, blowing nozzles for delivering currents of air between the front edges of the sheets and means having operative relationship with the control of the combing wheel actuation, whereby the supply of air is interrupted from the nozzles when the combing wheel is elevated, and the supply is established when the combing wheel is lowered.

52. In a sheet feeding machine, the combination of a sheet supporting table, a combing wheel, means for raising and lowering the combing wheel, a blowing nozzle for delivering a current of air between the front edges of the sheets, a valve for controlling the air supply thereto and means having operative relationship with the control of the combing wheel actuation for actuating the valve. 5
53. A sheet feeding device, comprising a drum, drum actuating means, a control for said actuating means comprising a caliper device, one caliper element actuated by the sheets and the other caliper element comprising a plate over which the sheets travel and means for changing the position of the plate with respect to the other caliper element. 10
54. In a sheet feeding device, the combination of sheet combining means, means for feeding a bank of sheets to the combining means, comprising a rotating drum, actuating means therefor comprising cooperating friction elements, sheet controlled means for controlling the efficiency of their engagement, and a cam timed to rock one of the friction elements in one direction during a portion of the cycle allotted to combing and to permit the return of the friction element while the sheet is being taken away. 15
55. A sheet feeding device comprising a table over which the sheets are fed, a drum for delivering sheets to the table, drum actuating means, a control for said actuating means comprising a caliper device, one element thereof actuated by the sheets passing beneath the same, the other element adjustably connected with the table over which the sheets pass. 20
56. In a sheet feeding machine, a sheet supporting table, sheet actuating means, a pivotally supported bracket, a freely rotatable pressure wheel connected therewith, means for braking the wheel and a support 45
57. In combination with a receiving device, having drop and feed rollers, a sheet feeding machine, comprising a sheet supporting table, sheet actuating means, a 50 freely rotatable pressure wheel, a pneumatically operated brake therefor and a pneumatic valve controlling said operation actuated by the drop roller mechanism.
58. In a sheet feeding machine, a combing wheel, pneumatically operated mechanism for lifting the combing wheel, a valve control therefor, mechanism for normally operating the valve at regular intervals, and a sheet controlled device for preventing such 55 operation. 60
59. In a sheet feeding machine, a combing wheel, pneumatically operated mechanism for lifting the combing wheel, a valve control therefor, a cam for normally operating the valve at regular intervals, and a sheet controlled device for preventing such operation. 65
60. In a sheet feeding machine, a combing wheel, pneumatically operated mechanism for lifting the combing wheel, a valve for controlling said pneumatic operation, a cam for normally actuating the valve at regular intervals and a device controlled by the advancing sheet for maintaining the valve out of the control of said cam actuation. 70
